UNITED STATES PATENT OFFICE.

WILHELM OESTERLEIN, OF CINCINNATI, OHIO.

CONDUIT ELECTRIC RAILWAY.

SPECIFICATION forming part of Letters Patent No. 554,719, dated February 18, 1896.

Application filed September 21, 1894. Serial No. 523,734. (No model.)

To all whom it may concern:

Be it known that I, WILHELM OESTERLEIN, a citizen of the United States, residing at Cincinnati, Ohio, have invented new and useful 5 Improvements in Electric Railways, of which the following is a specification.

My invention relates to electric street-railways, its object being to provide a practicable and efficient conductor and conducting 10 system whereby overhead trolley-wires may be dispensed with and the motor-current carried beneath the surface of the roadway.

To this end my invention consists, generally, in the construction and arrangement of 15 a metallic current-conducting rail and its supports in a tunnel between the tracks of the railway and in a traveling contact device for taking the current through the motor upon the car, the details of which will 20 more fully appear in the following specification, in connection with the accompanying drawings, illustrating preferred forms of construction, in which—

Figure 1 is a side elevation of the conducting-rail and one of its supports, partly sectioned; Fig. 2, a cross-section of the tunnel, showing one of the rail-supports in elevation; Fig. 3, a side elevation of the traveling contact device and its attachment; Fig. 4, an end 30 elevation of the same; and Figs. 5 and 6 are detail views illustrating construction of the same.

Referring now to the drawings, the general plan of construction embodies a sub-surface 35 tunnel T between the tracks similar to that of an ordinary cable railway and similarly provided with a continuous slot or opening through the surface having parallel walls spaced apart sufficiently to permit the passage of a contact device having a trailing connection with the car, and maintaining constant electrical communication between the car and the conducting-rail within the tunnel T.

As the construction of the tunnel forms no 45 part of my invention, the same need not be further described; but as the constant presence of moist air in a tunnel has been regarded heretofore as a serious objection to a 50 system of electrical conduction therein on account of the leakage of current through or over ordinary insulators I have devised the

following system of construction and maintenance of the conducting-rail.

The conducting-rail A is composed of rolled 55 bars of metal of sufficient strength to carry properly the traveling contact device (presently to be described) attached together and supported in the following manner: At suitable intervals, preferably at the junction of 60 each two rails, is arranged a supporting-stand B, constructed as follows: The stand proper is in the form of a deep cup resting upon a base-flange b and surrounded from a point above the base by a second cup b², rising above 65 the level of the first or inner cup, b'. All this may be formed as a single casting. Within the inner cup, b', is inserted a central stem, c, seated below in an insulating-socket d' at the bottom of the inner cup and centrally maintained in the axis of the said inner cup by an annular insulating-washer d² at or near the top of said cup. The stem c rises thence to a convenient height and carries the rail ends abutted in a socket-piece e, fitted 70 over it as a cap, and having horizontally-extended jaws between and through which bolts or rivets are passed through corresponding apertures in the web of the rail, after the manner of railway-fish-plate construction. Immediately above the mouth of the inner cup, b', a conical annular shield x' is placed, resembling an umbrella whose outer depending margin surrounds the mouth of the cup, extending below the horizontal level of the 75 mouth into the annular space of the outer cup; and above this and covering in like manner the mouth of the outer cup is a second larger shield x² of like form. Both these shields are preferably composed of hard rubber or "fiber" and are secured by a nut y threaded on the stem c above the upper shield, a ledge or shoulder of the stem below the lower shield, and an intervening washer or separating-collar, x³.

95 The insulating function of the device in addition to that of a mere support is realized by filling the cup-spaces with a non-conducting oil to or nearly to the level of the mouth of the outer cup, practically covering the lower shield. The upper shield diverts all 100 dropping moisture completely over and outside of the stand, while the inner shield diverts any condensation within the space covered by the

upper shield to the outer side of the inner cup, where it drops into the annular space and is from time to time removed and the supply of oil renewed to maintain practically 5 the above-described conditions. The actual support of the rail—namely, the stem *c*—is thus completely insulated from the stand *B* by the body of the insulating-oil, covered and protected by the shields both from undue 10 evaporation and from displacement by moisture at joints where the moisture could possibly form a conducting-bridge.

The trolley device *G* is a flat bar *g*, preferably of insulating material, extending vertically 15 through the surface-slot, and rests by gravity upon the conducting-rail, upon which it is guided by a grooved bearing-wheel *Z*. It is swiveled at its upper terminus to a trailing bar *h*, pivoted to the under side of the 20 car or framework of the car-truck, and is thus enabled to adjust itself to curvature of the track and slot. The swivel connection consists of a two-part ring-terminal *h'* at the end of the trailing bar, (so constructed for detachability,) embracing a cylindrical head *g'*, 25 mounted on the bar *g*. The two parts of the ring are pivoted together at one side and held by a suitable clamp *h*² at the diametrically-opposite side from the pivotal connection. 30 The fixed side of the ring has a lateral extension, as shown in Figs. 3 and 6, in which the end of the bar *h* has a swivel connection, said bar being held in place in said extension by means of the collar *o*'.

35 With reference to the electrical conductor, the construction is as follows: The bar *g* is provided with a central recess *g*², through which passes a suitably-insulated conducting-wire *w*, connecting below to a metallic shoe *i*, 40 in which the bearing-wheel *z* is pivoted. At the upper end of the bar *g* the conducting-wire *w* is carried, suitably insulated through the head *g'* and electrically connected to an elbow *j*, to which a continuation *w'* of the wire 45 is attached, and is carried thence along the trailing-bar to the motor. (Not shown.)

To protect the contact device from the effects of moisture, the following attachments are provided: First, an umbrella cap or shield 50 *l* is connected to the elbow *j* and completely covers the top of the device, to shed any dripping moisture. To intercept any moisture condensing and flowing down the sides of the bar *g*, an annular flange *l* is secured to 55 the bar above the shoe *i*, forming an annular cup surrounding the same, which is filled with oil when in use. Over this an umbrella-shield *m* is secured to the bar *g*, completely overlapping the annular cup and diverting any 60 trickling moisture. There is thus formed an interposed barrier of oil in contact with the bar *g*, besides the shield which serves to protect the parts from splashing mud or moisture and to preserve the oil to some extent from evaporation. The device, as thus constructed, effectively prevents any short-circuiting of 65 metallic parts by moisture.

To retain the bar *g* (which is somewhat extended in a fore and aft plane) in normal line with the trailing bar *h*, the swiveling head is 70 retained by a circular spring, ring *m*, connected at one side to the bottom of the head *g'*, and extending thence eccentrically around the head, and cut radially so as that its free ends may bear oppositely against a lever projection *o* of the arm *h*. The head *g'* being rigidly connected to the bar *g*, any variation of alignment of the latter with the trailing arm *h* in either direction is resisted by the 75 spring.

I claim as my invention and desire to secure by Letters Patent of the United States—

1. A support for electric conductors embodying a supporting-stem and a stand in which the same is carried, provided with 85 means for maintaining a body of oil surrounding and in contact with the stem in such relation as to prevent or intercept the passage or accumulation of any moisture that might connect the stem and stand electrically, substantially as set forth.

2. A support for electric conductors embodying a supporting-stem, a cup-shaped stand carrying the stem in suitable insulations, and one or more shields surrounding the 95 stem and covering the mouth of the stand, substantially as set forth.

3. A support for electric conductors embodying a supporting-stem, a stand in which the stem is socketed in suitable insulations, 100 an annular cup or flange surrounding the stand and extending above the same, an umbrella-shield surrounding the stem above the socket and depending into the annular space of the surrounding cup, and a second shield 105 surrounding the stem above the first and covering and depending externally around the mouth of the annular cup, substantially as set forth.

4. In a support for electric conducting-rails, 110 the combination of the cup-shaped stand, the stem socketed therein, and the head surmounting the stem having parallel flanges adapted to receive and clamp between them the abutting ends of the conducting-rails, substantially as 115 set forth.

5. In a system of conduction for electric railways, the combination with the motor-car and a sub-surface conducting-rail, of a contact-support consisting of an approximately 120 horizontal trailing arm, pivoted to the car body, and a vertical contact-arm, extending thence through the tunnel-slot to the conducting-rail, the trailing and vertical arms swiveled together horizontally and vertically, substantially as set forth.

6. In electric apparatus, a trailing contact-support, consisting of a vertical arm adapted to rest upon a sub-surface conducting-rail and extend thence through the tunnel-slot, an approximately horizontal arm adapted to be pivotally attached to the car, and a detachable connecting element, having a swiveling connection with both the vertical and horizontal 130

arms and connecting both together, substantially as set forth.

7. In a contact-support of the character indicated, a vertical arm, adapted to pass through the tunnel-slot and terminated above by a cylindrical head, an embracing-ring adapted to engage as a swivel upon the cylindrical head, with a lateral extension adapted to receive the trailing arm, and a split-ring spring, and 10 engaging the lateral extension of the embracing-ring between its terminals and secured at the opposite side to the cylindrical head below the embracing-ring, substantially as set forth.
8. In a trailing contact-support of the char-

acter indicated, in combination with the vertical arm having a cylindrical head, a split embracing-ring hinged at the one side and provided with a detachable fastening at the other, and an extension adapted to engage pivotally with the trailing arm, substantially as set 15 forth.

In testimony whereof I have hereunto set my hand in the presence of two subscribing witnesses.

WILHELM OESTERLEIN.
